UNITED STATES PATENT OFFICE.

FLOYD K. RICKS, OF CANTON, ILLINOIS.

DUMP-BOX AND FRAME.

1,308,507.

Specification of Letters Patent.

Patented July 1, 1919.

Application filed October 11, 1917. Serial No. 195,974.

To all whom it may concern:

Be it known that I, FLOYD K. RICKS, a citizen of the United States, residing at Canton, in the county of Fulton and State of Illinois, have invented a new and useful Dump-Box and Frame, of which the following is a specification.

It is the object of this invention to provide novel means for mounting and controlling the movements of a tilting and bodily-slidable box constituting a part of a dumping wagon.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

Practical embodiments of the invention are shown in the accompanying drawings, wherein:

Figure 1 is a bottom plan view of a dump box and frame constructed in accordance with the invention;

Fig. 2 is a side elevation of the same;

Fig. 3 is a vertical longitudinal section of the device;

Fig. 4 is a front elevation of the gripping plate, a fragment of the box shown in section.

Referring to the drawings by characters of reference:

A frame indicated generally by F. is provided and rests upon a running gear R. while it supports a box B.

The frame F. is composed of cross bars or bolsters 1-1 which are adapted to rest above the front and rear axle of the running gear, and which supports the side boards 2 of the frame. The side boards 2 are joined at their forward ends by a head board 3 which may be arranged on an incline, as shown, and by a foot rest 4 which overlies the side boards 2 and the head board 3. A rear cross-bar 5 is also rigidly secured between the side boards 2.

Standards 6 may be secured to each side board 2 adjacent the foot board or rest 4 and a seat 7 may be supported on these standards.

A shaft 8 extends transversely of the frame and projects beyond the side boards

2 in which it is journaled. Rigid on the shaft 8 and preferably near the center thereof, is a toothed or ribbed wheel 9 formed with a central longitudinal groove.

Another shaft 10 extends transversely of the frame toward the rear thereof, and the ends of this shaft rest in horizontal grooves formed in blocks 11-11 which are secured to each side board 2. A pulley 12 turns on the shaft 10 and hook bolts 13 engage the shaft on each side of the pulley, and have their threaded ends passed through apertures formed in the rear cross-bar 5 to which they are secured by nuts 14. As will be understood, the nuts 14 are manipulated to adjust the tension of a chain 15 which passes about the wheel 9 and the pulley 12.

As the chain 15 passes over the ribbed wheel 9, the links arranged edgewise are accommodated by the groove while the links which lie flat upon the wheel are received between the teeth or ribs and so form a positive drive which will not slip.

On one extending end of the shaft 8 is secured a pinion 16 which is engaged by the catch (not shown) of a lever 17. The lever 17 is bifurcated and spread at its lower end to straddle the pinion 16 and is pivotally mounted on the shaft 8. The latch of the lever 17 is formed at one end of a rod 18 which slides in the lever 17 and is normally held in its outer or unlatched position by a coiled spring 19 which surrounds the rod. The rod 18 extends beyond the end of lever 17 and is provided with a hand knob 20 to permit the rod to be easily manipulated to throw it to latching position.

A pawl 21 is pivoted to a side board 2 and engages the pinion to lock the shaft against turning. The pawl is formed with an arm which extends above the foot rest 4 and is provided with a treadle 22.

Another shaft 23 extends transversely of the frame F., at the forward end of said frame, and the ends of this shaft are journaled in the side boards beyond which they preferably project.

A pinion 24 is rigid on one projecting end of the shaft 23, and this pinion is straddled by the bifurcated end of a lever 25 which is similar to and operates as the lever 17, just described.

A pawl 26, pivoted to a side board 2, is operated by a treadle 27 to contact the pinion and lock the shaft 23 against turning.

A pulley 28 is rigid on the shaft 23 and

to the pulley is secured one end of a chain 29 which passes under a guide pulley 30, journaled on a pin 31 which is secured in one side board 2, and the other end of which 5 is secured to the forward end of the dump box B.

The box B. is a usual rectangular box, to each side of which is secured a V shaped casting 32. The castings 32 are so positioned that the vertex or bend of the V extends below the side of the box and this portion of each casting is apertured to receive the end of a rod 33 which may be held in position therein by nuts 34 which are threaded on the ends of the rod or in any other suitable manner. The rod 33 may also be supported by lugs 35 which are secured to the bottom of the box and spaced from the castings 32.

10 Each end portion of the rod 33 lying between a casting 32 and a lug 35 is adapted to enter an opening 36 defined by the ends of a retaining bar 37 secured to the upper edge of each side board 2, near the rear 15 thereof. Each bar 37 has its ends bent back to overlie itself, as seen most clearly in Figs. 2 and 3, and thereby forms a slot in which the rod 33 is free to reciprocate longitudinally of the frame, and to pivot when the 20 rear end of the box overhangs the frame sufficiently.

25 30 Each end portion of the rod 33 lying between a casting 32 and a lug 35 is adapted to enter an opening 36 defined by the ends of a retaining bar 37 secured to the upper edge of each side board 2, near the rear thereof. Each bar 37 has its ends bent back to overlie itself, as seen most clearly in Figs. 2 and 3, and thereby forms a slot in which the rod 33 is free to reciprocate longitudinally of the frame, and to pivot when the rear end of the box overhangs the frame sufficiently.

A rod 38 is arranged transversely of the box and secured beneath the forward end thereof by brackets 39. The ends of this 35 rod 38 are adapted to take under the inwardly projecting flanges of angle bars or plates 40, one of which is fastened to each side board of the frame. The engagement of the bar ends under the flanges retains the 40 forward end of the box in lowered position, while, at the same time, allowing the box to slide longitudinally upon the frame.

A plate 41 is secured to the bottom of the box B and is formed with a downturned 45 bifurcated end 42 which is adapted to straddle the chain 15.

Standards 43 are secured to and rise above each side of the box at the rear end of the box and a rod 44 extends between the upper

ends of these standards to which it is secured. 50

Lugs 45 secured to a tail board 46 pivotally engage the rod 44, thereby allowing the tail board to swing from the rod, as the box is tilted to dumped position. Cleats or stops 55 47 are secured to each side of the box and limit the inward swing of the end gate 46.

Having thus described the invention, what is claimed as new and sought by Letters Patent, is:—

60 In a device of the class described, a frame comprising side members and a rear cross bar; a forward shaft journaled in the side members; a rear shaft; means for mounting the rear shaft on the side members, for rotation and for adjustment longitudinally of the frame; an endless chain assembled with the shafts and comprising links; retainers mounted on the upper edges of the side members and having overhanging ends spaced 70 to define an opening in the top of each retainer; a body having side trunnions insertible into the retainers through the openings, the trunnions being mounted to rock in the retainers and to move longitudinally of the 75 retainers, thereby permitting a tilting of the body and a reciprocatory sliding movement thereof; a depending projection on the body in front of the trunnions, the projection being bifurcated to receive one of the links of 80 the chain, and being adapted to be received between adjoining links of the chain whereby the chain may advance the body; a tightener mounted on the rear cross bar and co-operating with the rear shaft to position 85 said link for reception between the bifurcations of the projection, the trunnions co-operating with the forward ends of the retainers to cause the projection to engage with said links; and means at the forward end of 90 the frame for rotating the forward shaft.

In testimony that I claim the foregoing as my own, I have hereto affixed my signature in the presence of two witnesses.

FLOYD K. RICKS.
